UNITED STATES PATENT OFFICE.

HERON P. CHASE, OF DETROIT, MICHIGAN, ASSIGNOR TO GENERAL MOTORS RESEARCH CORPORATION, OF DETROIT, MICHIGAN, A CORPORATION OF DELAWARE.

COMPENSATING-ENGINE MOUNTING.

Application filed December 24, 1926. Serial No. 156,973.

This invention relates to mountings for internal combustion engines and the like, and more particularly to a device to compensate for vibrations caused by unbalanced forces 5 upon the operation of the engine.

The invention is especially useable in connection with engines of the four cylinder type employed to propel motor vehicles and will be so described herein. In this type of engine the pistons are reciprocated by pairs in opposite directions, that is two of the pistons travel toward the extreme upper limit as the remaining pair of pistons move toward the extreme lower limit. At the opposite limits, 10 the reciprocation of the pistons is slowed down, since the crank shaft swing is concentrated on a sidewise movement, whereas when its swing becomes vertical, the piston velocity is greatly increased. This unison deceleration 15 and acceleration of the group of pistons results in a vibratory crankshaft revolution. The inherent vibration is very small, amounting to but a few thousandths of an inch. Its frequency, however, transmitted thruout the 20 entire frame and automobile body, is disagreeable to the nervous system of passengers, as well as causing breakage of parts, detracting from motor efficiency and also setting up undesirable noises when the rate of 25 movement comes into resonance with certain parts of the automobile.

In the customary engine unit, the inherent vibrations act in a plane intermediate the group of pistons, which is forward of the center of mass of the engine. Consequently 30 by providing pivotal supports at rear of the engine unit on a transverse horizontal axis, at or adjacent the point of neutral reaction, the rear supports are entirely relieved of 35 vibration, while the unit oscillates bodily about such rear pivotal supports thru an up and down movement, which is therefore, particularly pronounced at the front of the engine. In order to entirely relieve the chassis 40 frame of such vibratory movement, the present invention contemplates a front suspension embodying a two lobed or elliptical cam on the crankshaft or other engine shaft mounted in a bearing on the chassis frame, so that with every crankshaft revolution, the 45 engine is twice carried bodily thru an up and down movement in synchronism with engine vibration. The range of positive movement under influence of engine operation is calibrated in accordance with the amplitudes 50

of inherent vibration, and thus offsets its effects.

In the accompanying drawing, illustrating a preferred but not necessarily the only mode of carrying the invention into effect, Figure 60 1 is a front elevation of the mounting secured to the transverse chassis frame member. Figure 2 is a fragmentary view, partly in section showing the engine crankshaft carried in the mounting, and its driving connection 65 with the radiator fan. Figure 3 is an enlarged detail view of an anti-friction roller bearing, having an eccentric inner face to which the engine shaft is keyed, for imparting the vibration compensating movement to 70 the engine.

In the construction of automobiles, a transverse member, indicated in the drawing at 10, connects the front of the longitudinal side chassis frame members, one of which is shown in dotted lines in Figure 1. In three point engine suspension arrangements, the central front support is located at the center of the cross member 10. According to the usual practice, a circular housing or casing 11 is 75 secured to the cross member 10 by bolts 12. Projecting ears or lugs 13 on the housing 11, provide anchorage for bolts 14, to secure a closure plate 15 to the housing. An anti-friction element or bearing is located within 80 the housing 11, and preferably consists of a circular series of rollers 16, carried by retaining rings 17—17 on opposite sides, and these rollers run between outer and inner races 18 and 19 respectively. The inner race 19 is 85 keyed to a stub shaft 20, provided with a circular opening into which a reduced portion 22 of the engine crank shaft 23 extends, and the stub shaft 20 in turn, is secured to the engine crank shaft 23 by the key 24. The gear 90 25 may be carried on the shaft to actuate in the usual manner, an ignition distributor unit and cam shaft. A pulley wheel 26 is shown keyed to the reduced portion 27 of the stub shaft 20, having its hub extended forwardly 95 and notched at 28 for engagement with a hand crank, in case it is desired to revolve the crankshaft 23 by manual effort to start the engine. The driving belt 29 connects the pulley 26 with the usual radiator fan 30. 100

Referring more particularly to Figure 3, it will be noted that the outer circular roller race 18 is formed in a true circle, while the inner roller race 19, which is keyed to the stub shaft 20, is eccentric or in the nature 110

of a two lobbed cam. That is, it is provided with two diametrically opposite high points. In the drawing the largest diameter is shown as being on a vertical line, with the periphery generally receding to the opposite low points, ninety degrees from the respective high points. For illustrative purposes, a true circle having the maximum cam diameter, is inscribed in a dotted line. It will be understood, however, that the degree of recession is somewhat exaggerated in the drawing, the actual range thru which the engine is varied being quite small, in accordance with the low amplitude of inherent engine vibration.

15 From the above description, it will be seen that as the engine crankshaft rotates, the double lobbed eccentric inner bearing race, imparts to the engine a movement corresponding to and timed with the reaction of the unbalanced moving parts, whereby the inertia thereof is effectively overcome and the supporting frame is relieved of the damaging and disagreeable strains.

20 While the parts and arrangement have been described more or less specifically, it is to be understood that the invention is not to be limited to the exact form shown, but that such obvious modifications may be made as come within the scope of the appended claims.

25 30 Having described the invention, I claim:

1. A vibration compensating mounting for bodies having unbalanced operating parts producing body vibrations, including the combination of a fixed member, a relatively movable cam member bearing on the fixed member and operated with the movement of said operating parts to impart to the body a movement in synchronism with said body vibrations and an anti-friction element interposed 35 between said members.

2. The combination with a body having moving parts that produce inherent vibration and a supporting frame therefor, of means connecting the frame and body including 40 relatively movable members bearing one on the other, one of which has an irregular bearing surface which upon relative movement of the members varies the position of the body relative to the frame in synchronism with body vibrations, and an anti-friction element disposed between said relatively movable members.

3. The combination with a body having moving parts that produce inherent vibra-

tion, and a supporting frame therefor, of a bearing fixedly secured to the frame, and a moving part of said body mounted in said bearing, having an irregular bearing surface, such irregular bearing surface upon movement of the part causing a relative movement 55 of the body and frame to compensate for the inherent vibration.

4. The combination with a body having moving parts causing vibration and a supporting frame therefor, of an anti-friction bearing carried by the frame, and a moving part projecting from the body and mounted in said bearing, said moving part having an irregular bearing surface to impart a movement to the body in synchronism with said vibration.

5. In an engine mounting, the combination with an engine having a crank shaft and a supporting frame, of an anti-friction bearing fixedly secured to the frame, and a rotary cam associated with the engine crank shaft and mounted in said anti-friction bearing to support the engine and, adapted upon operation of the engine to vary the position of the engine in relation to the frame to compensate for engine vibration.

6. The combination with a supporting frame and an internal combustion engine supported thereby and having a crank shaft, the moving parts of which engine result in a relative vibration of the engine in its frame, of a vibration compensating connection between the frame and engine, including, a rotary cam carried by the engine crank-shaft, having a pair of diametrically opposite high points 85 and a pair of low points receding from the respective high points, and an anti-friction bearing for the cam fixedly carried by the frame, whereby upon engine operation, the engine is given a relative movement with the frame in synchronism with engine vibrations.

7. The combination with an internal combustion engine having moving parts resulting in vibration and a supporting frame therefor, of means connecting the engine to 100 the frame and adapted to vary the position of the engine relatively to the frame in synchronism with engine vibrations, including an eccentric roller actuated by a moving part of the engine, and a bearing therefor fixedly 105 carried by the frame.

In testimony whereof I affix my signature.
THERON P. CHASE.
